MASSAGE APPARATUS

Benjamin Hill, Wayne, Pa.

Application August 18, 1939, Serial No. 290,823

9 Claims. (Cl. 128—57)

This invention relates to massage apparatus.

The object of the invention is to provide massage apparatus which is of simple and sturdy construction, which massages more specifically those parts of the body in which massage is most beneficial, and which comprises a simple and complete adjustability to vary the vigor, the locus of application, and in large measure the sort, of the massage treatment which it gives.

10 In the accompanying drawings Fig. I is a plan view of a massage table made in accordance with my invention. Fig. II is a side elevation thereof. Fig. III is a fragmentary plan view of the supporting structure for the massage table and the 15 actuating means therefor, taken in the plane of the section line III—III of Fig. IV. Fig. IV is a fragmentary vertical sectional view of the portion of the massage table shown in Fig. III, taken in the plane of the section line IV—IV of Fig. III. 20 Fig. V is a cross-sectional view through the massage table taken through the slots in which the spine massaging members are located, and showing the adjustable mounting of those members.

In the illustrative embodiment of my invention, 25 reference numeral 1 designates a supporting frame on which the massage table proper 2 is reciprocably mounted by wheels 3 running in longitudinal tracks 4. The organization of the apparatus is such that the massage table proper 30 2 is reciprocated longitudinally of the supporting frame 1 by its reciprocating movement to give the desired treatment. The reciprocating movement of the table 2 is regulable in length and coincidentally in rapidity.

35 Table 2 is driven from an electrical motor 5 by speed-reducing connection to a crank wheel 6. This speed-reducing drive comprises two large diameter sheaves 7 and 8 carrying small diameter pulleys 7a and 8a; a small diameter pulley 9 on the armature shaft of the motor, and belts 10, 40 11 and 12 connecting the crank wheel 6 with the motor 5 by way of the large diameter sheaves and small diameter pulleys. Crank wheel 6 has thereon means for regulating the length of stroke imparted to the table 2. Such means are shown 45 as a crank bracket 13, having therein pintle holes 14 in any of which there may be engaged the wrist pin 15 of a crank arm 16 pivotally connected at 17 to the table 2.

50 An important massage effect obtainable by use of my massage apparatus is that of a back and spinal massage, which may be made effective throughout a greater or lesser length of the human spine. Means for effecting this massage are shown as two roller disks 18 mounted on a cross-shaft 19 which may be rotatable, or upon which the disks may rotate. These disks extend through slots 20 in the reciprocable table, and the slots 20 are of sufficient length to permit the maximum length of table stroke of which the adjustable

5 crank connections are capable. They also are of sufficient width to permit some adjustment of the disks 18 toward and away from each other.

Assuming that a person lies face-up on the 10 table, with the spinal region disposed in line with the interval between the disks 18, reciprocating movement of the table carries the person massaged along the roller disks with his or her spine lying between them. In accordance with the 15 length of the person's back which it is desired to massage in each movement of the table, adjustment of the table stroke may be made. That adjustment need be made only infrequently. It is useful frequently so to adjust the position of the roller disks 18 that they project a greater 20 or lesser distance above the upper surface of the table. To this end the cross shaft 19 which carries the roller disks 18 is made readily adjustable by mounting the end brackets, or bearings 21 of the shaft on, or as part of, vertically extended 25 racks 22, movable in guides 23. Pinions 24 carried by a cross shaft 25 act simultaneously on the two racks 22 to raise or lower roller shaft 19. At one end, pinion shaft 25 carries a hand wheel 26 by which it may be rotated.

This vertical adjustment permits adaptation 30 to the body region which is massaged, as for comparison to the neck or lower back region of the person receiving massage. It also permits the massage in a selected region of the person's 35 body to be more or less vigorous, as may be desired, in each individual case; and permits the vigor of the massage treatment to be increased or decreased as it proceeds.

The apparatus also comprises adjustable means 35 for massaging the legs of a subject, which means may be used, either alone, or in conjunction with the back-massaging means. The leg massaging means of the apparatus is in the form of a pair of contoured rolls 27 mounted by a cross shaft 40 28 at a level above the surface of table 2. As shown, cross shaft 28 is vertically adjustable in the assembly, being carried on vertical bracket arms 29, having therein a series of perforations 29a. It is also adjustable by cooperation of the 45 vertical bracket arms 29 with two horizontal side brackets 30 provided with a series of perforations 30a. By inserting pins 31 at each side of the table in a selectively matched pair of perforations 29a of a vertical bracket and 30a of a horizontal bracket, a single operation may serve adjustably 50 to position rollers 27 both vertically and horizontally with respect to the surface of table 2.

The utility of leg-massaging rolls 27 is apparent. If the legs of a person resting on the table 55 lie upon rolls 27, movement of the table, carrying the legs of the person over these rolls, gives an effective massage treatment to the legs. By adjusting the rolls, and adjusting the position of the person on the table, a massage may be given 60

his legs from the ankles to the hips, and the adjustability is found particularly desirable in massaging difficult regions, such as the inner part of the knee joints and the ankles. Assuming that 5 both the back-massaging roller disks 18 and the leg-massaging rollers 19 are to be used simultaneously, longitudinal relative adjustment of these massaging agencies is of particular advantage inasmuch as it permits them to be spaced 10 to operate simultaneously upon selected body regions of persons taking the massage. It also permits both massage treatments to be performed simultaneously, on selected body regions of persons of very different height. The adjustability 15 of the massaging agencies both individually and relatively gives the apparatus ability by an extremely simple structure to perform a wide range of massaging functions.

The leg-massaging rolls 27 have a further 20 function co-operative with the back-massaging function of the roller disks 18. This is because, by supporting the legs of a person taking massage at a selected height, they tend properly to position the back of that person with respect to 25 the back-massaging disks.

In the usual use of the apparatus, the subject lies relaxed upon the table, or body-supporting platform, with his or her spine between, or in line with, the interval between the roller disks 30 18. The position of the subject longitudinally of the table or platform is primarily determined in accordance with the spinal region for which massage is chiefly desired. Since the mounting of the roller disks is rigid, they are adjusted vertically to give an adequate pressure on both sides of the spine without undue discomfort to the subject. The length of stroke is adjusted, primarily to cause the body in reciprocation of the 35 table or platform to traverse the rollers in the spinal region which is to be massaged, so that the massage may be adequately applied without incurring any danger from a stroke of such length as undesirably to act upon any spinal region. It is to be emphasized that the subject may be, and desirably is, wholly relaxed during the 40 massage treatment.

Whereas the disks 18 and the contoured rolls 27 have been herein defined respectively as back-massaging members and leg-massaging or leg-supporting members, such description is definitive merely of their primary function in massage. Both may be utilized in massaging other regions of the human body and the terms used are, 45 therefore, to be taken as terms of description and not as terms of limitation. It is clear that other changes may be made in the form and arrangement of the elements of my massage apparatus, as well as in the utilization of those elements without going beyond the scope of my invention as defined in the appended claims.

I claim as my invention:

1. In massage apparatus the combination of a 50 horizontally reciprocable body-supporting platform, a plurality of diversely formed sets of body-contacting members mounted in cooperative position with respect to the said body-supporting platform and adjustable both toward and away from each other in a longitudinal direction and 55 vertically with respect to the said body-supporting platform, and power actuated driving means and connections for reciprocating the body-sup-

porting platform with respect to the said body-contacting members.

2. Massage apparatus in accordance with the definition of claim 1 having in the driving connections for the said body-supporting platform 5 an adjustable stroke connection, variably determining the length of movement of the said body-supporting platform with respect to the said body-contacting members.

3. Massage apparatus in accordance with the 10 definition of claim 1 in which the body-contacting members of one of the said diverse sets are contoured rolls and in the other of the diverse sets are roller disks.

4. In massage apparatus the combination of 15 a horizontally reciprocable body-supporting platform with a set of back-massaging rollers projecting through the said body-supporting platform, a leg support mounted in regulably spaced relation to the said set of back-massaging rollers, 20 and power actuated driving means and connections for reciprocating the said body-supporting platform with respect to the said back-massaging rollers.

5. In massage apparatus the combination of 25 a horizontally reciprocable body-supporting platform with a set of roller disks projecting through the said body-supporting platform in closely spaced relation, vertically adjustable mounting means for the said set of roller disks, and power 30 actuated driving means and connections for reciprocating the said body-supporting platform with respect to the said set of roller discs.

6. In massage apparatus the combination of a 35 horizontally reciprocable body-supporting platform with a set of back-massaging rollers projecting through the said body-supporting platform, a leg support, an adjustable mounting for the said leg support giving vertical adjustment thereof and regulable spacing from the set of 40 back-massaging rollers, and power actuated driving means and connections for reciprocating the said body-supporting platform with respect to the said back-massaging rollers.

7. Massage apparatus in accordance with the 45 definition of claim 6 having in the driving connections for the said body-supporting platform an adjustable stroke connection, variably determining the length of movement of the said body-supporting platform with respect to the said 50 back-massaging rollers.

8. Massage apparatus in accordance with the 55 definition of claim 6 in which the back-massaging rollers are carried by mounting means which are vertically adjustable with respect to the said body-supporting platform adjustably to determine the projection of the said back-massaging members above the surface level of the said body-supporting platform.

9. In massage apparatus the combination of a 60 horizontally reciprocable body-supporting platform with a set of back-massaging rollers projecting through said body-supporting platform in closely spaced relation, vertically adjustable mounting means for the said set of back-massaging rollers, and power-actuated driving means and adjustable stroke connections thereto for reciprocating the said body-supporting platform with respect to the said back-massaging rollers 65 and for varying the length of the reciprocating movement of the said body-supporting platform.

BENJAMIN HILL.
